[57] CLAIM

The ornamental design for an isolateral dumbbell press exercise machine, as shown and described.

DESCRIPTION

FIG. 1 is a perspective view of an isolateral dumbbell press exercise machine embodying my new design.

FIG. 2 is a front elevational view thereof.

FIG. 3 is a side elevational view thereof, the opposite side being a mirror image thereof.

FIG. 4 is a rear elevational view thereof.

FIG. 5 is a top plan view thereof.

FIG. 6 is a bottom plan view thereof.

FIG. 1

FIG. 2

FIG. 3

FIG. 4

FIG. 5

FIG. 6
